UNITED STATES PATENT OFFICE.

WILLIAM S. SOUTHWICK, OF CLINTON, MASSACHUSETTS, ASSIGNOR TO WICKWIRE SPENCER STEEL CORPORATION, OF WORCESTER, MASSACHUSETTS, A CORPORATION OF MASSACHUSETTS.

WIRE-FILLING CUTTER FOR WIRE-FABRIC LOOMS.

Application filed March 5, 1921. Serial No. 449,836.

To all whom it may concern:

Be it known that I, WILLIAM S. SOUTHWICK, a citizen of the United States, residing at Clinton, in the county of Worcester 5 and State of Massachusetts, have invented new and useful Improvements in Wire-Filling Cutters for Wire-Fabric Looms, of which the following is a specification.

This invention has for its object the production of a wire filling cutter for wire fabric looms.

Referring to the drawings wherein like characters indicate like parts wherever they occur:—

15 Figure 1 in side elevation shows a wire filling cutter constructed in accordance with my invention mounted in position on the right hand side of a fabric loom, a portion only of the framework of the loom being shown, the lay being shown partly in section and partly in end elevation; the cutter as shown in this figure is in its inoperative position; the parts appear as viewed from the left hand side of the loom.

20 Figure 2 is a detail view showing parts omitted in Figure 1 but which if present in said figure would be in front of the parts therein shown.

25 Figure 3 is a view similar to Figure 1 showing the cutter advanced in operative position for its first cutting operation.

30 Figure 4 is a view similar to Figure 2 showing the parts in the position they occupy when the cutter is advanced in the position shown in Figure 3.

35 Figure 5 is a view similar to Figure 3 but with the cutter and cutter lever removed showing the parts behind the cutter and cutter lever in the position in which they appear in Figure 3.

40 Figure 6 is a detail view of the parts shown in Figures 3 and 5 in the position they assume after the first cutting operation and just prior to the second cutting operation, the rear side of the lay being shown in outline; the completion of the motion of the lay to the right in Figure 6 would first operate the cutter and next the trip to release the cutter, and permit it to return to its inoperative position or that of Figure 1.

45 Figure 7 in side elevation shows the cutter, cutter lever, and the shaft upon which the cutter lever is mounted; a horizontal full line being used to represent the right

selvage edge of the cloth just beyond which the cutter is positioned.

55 Figure 8 is a front elevation of the parts shown in Figure 7, a vertical broken line representing the selvage edge of the cloth, while a horizontal broken line represents the filling in the position it occupies when being cut.

60 Figure 9 is a detail view of the movable jaw of the cutter.

65 Figure 10 is an end elevation of the parts shown in Figure 9.

70 Figure 11 is a cross sectional view on line 11—11 of Figure 9, looking in the direction of the arrows, showing the movable jaw of the cutter and its cutter blade.

75 Figure 12 is a top plan view of the cutter and its associate parts, that is the top plan view of the apparatus with the parts shown in Figure 2 in position in front of the parts shown in Figure 1.

80 Figure 13 is a front elevation of the parts shown in Figure 12, or a representation of said parts as they appear when looking at them from the front of the machine. In this figure castings appear that are not shown in Figure 12.

85 Figure 14 is a diagrammatic view showing the position of the filling at the time of the first cutting operation or cutting of the spent filling, that is just before the old filling unit is removed from the shuttle; this view also shows in a diagrammatic way the cutter, the lay, the new filling unit and the guide for the free end of the new filling.

90 Figure 15 is a view similar to Figure 14 of the parts as they appear at the second cutting operation or when the free end of the new filling is cut.

95 Figure 16 is a side elevation of the bracket, guide for the free end of the filling and the weight connected to the free end of the filling constituting the end tension, these parts appearing in top plan view in Figures 14 and 15.

100 1 represents a portion of the right side of the framework of a wire fabric loom; 2 one of the girts which extend crosswise of the loom and are connected to and supported by the side frames 1 at either side of the loom. This construction is common and needs no further description. In Figures 1, 3 and 5, is represented the usual lay for wire fabric looms comprising a lower

beam 3, and an upper beam 4 connected at either end by uprights 5. 6 represents the usual reeds for wire looms carried by cross beams 3, 4. Referring to Figures 14, and 15, 5 the upper beam 4 of the lay is shown in top plan outline. In this type of loom the shuttle is carried by a bar supported by the lay. 8 is a conventional representation of a spool for carrying the wire filling which in practice is arranged in and carried by the shuttle. 10 represents a bracket connected with the framework of the machine provided with a guide 11 over which the free end of the filling passes to a weight 110, see Figure 16, or other end tension device. The 15 supports and operating mechanisms for a lay, shuttle, etc. are not shown, forming no part of the present invention.

Referring to Figures 1 to 13, 12 represents an oscillating shaft. This shaft at either end is mounted in a bearing 12^a formed at 25 the upper end of the casting 12^b secured by lag screws 12^c to opposite ends of the girt 2, only the right hand bearing appearing in the drawings. This shaft is operated by mechanism, not shown, whose time of operation 30 is controlled by a filling feeler forming no part of this invention. 13, Figure 13, represents a collar secured to the shaft 12 by a set screw 14. 15 represents a coiled spring on the shaft 12, one end being secured to the 35 collar 13, the other end being secured to bearing 12^a in a common manner. The purpose of the spring 15 is to yieldingly resist the oscillation of the shaft 12 by the instrumentalities heretofore described and to return said shaft 12 to its initial position.

16 represents a lever, one end of which is secured to the shaft 12 by a set screw 17, see Figure 5. 18 represents an arm on said lever 16 provided on its lower side and near its rear end with a lug 19. 20 represents a swinging bunter pivoted at its top end on a stud 21 carried by the rear end of the lever 18. The upper end of the bunter is formed as a finger or tail piece 22 adapted by engagement with the lug 19 to limit the motion of the bunter in the direction of the hands of a watch, in Figure 6. The lower end of the bunter 20 is formed with a buffer member 23. As shown in Figure 13, the lever 16 55 is at the right of the bearing 12^a. Upon the shaft 12 and to the left of the collar 13 is rigidly secured a gear segment 24 by means of a split boss having ears 25, 25, held together upon the shaft 12 by a set screw 26, 60 see Figure 4. Upon the free end of the gear segment 24 are formed two gear teeth 27, 27. 29 represents a casting secured upon the girt 2, see Figure 2, and formed with a forwardly projecting arm 30 carrying at its upper end 65 a perforated boss 31. Referring to Figures

2 and 4, there is a bell crank lever comprising arms 35 and 36, and this lever at its angle or elbow carries a boss arranged on the stud 34. The outer end of one arm 35 of this bell crank lever is arranged between the 70 gear teeth 27, 27, while the outer end of the other arm 36 of this bell crank lever is arranged between the gear teeth 38, 38 of the gear segment 39, that at its end is formed with a boss 40 loosely mounted upon a shaft 75 41. The shaft 41 in turn is arranged in a bearing 42 carried by an arm 43 projecting from the casting 29. Upon the left hand end of the shaft 41, see Figure 12, is mounted an adjustable collar 44 adapted to be secured 80 at any desired position upon the shaft 41 by a pin 45 in the usual way. 46 represents a coiled spring mounted on the shaft 41, the left hand end of this spring being arranged in the collar 44, the right hand end of the 85 spring 46 being secured in the boss 42. The purpose of the spring 46 is to yieldingly resist the motion of the shaft, in Figure 2, in a direction opposite to the motion of the hands of a watch and, when the power is released, 90 to turn the shaft in the direction of the hands of a watch until it returns to its original position. 41^a represents a bearing, see Figure 12, for the right hand end of the shaft 41, said bearing extending from a plate 41^b 95 secured to the framework by lag screws 41^c. 47 represents a boss arranged upon the shaft 41 and rigidly secured thereto by means of a set screw 48. This boss is formed with an arm 49 carrying at its end a laterally projecting finger 50 arranged over the arm 39 of the gear segment, see Figures 2, 4 and 12.

Referring to Figures 2, 4 and 12, when the shaft 12 is operated as heretofore described, such movement of the shaft will be 105 opposite to the hands of a watch. This movement is through a small arc. Assuming the parts to be in the position shown in Figure 2, which is the normal and inoperative position, such movement will throw the 110 teeth 27, 27 to the right, lifting the arm 36 and the teeth 38, 38 and rocking the shaft 41 in the direction opposite the movement of the hands of a watch. This will carry the parts to the position shown in Figure 4, 115 lifting the finger 50 and rocking the shaft 41 against the tension of the spring 46. When the power heretofore referred to is released from the shaft 12, the spring 46 through the action of the lever 49 and the finger 50 and the gear segment 39 will rock the shaft 41 in the direction of the movement of the hands of a watch and return the parts to the position shown in Figure 2. 51 represents a pintle carried by a casting 125 52 secured at its lower end to the girt 2, see Figure 7, the top of the casting being broken away in Figure 5. Upon the pintle 51 is loosely arranged a boss 53, see Figure 12, from the upper side of which projects 130

an arm 54, see Figures 5 and 13, formed on its rear face with two locking notches 55, 56 and above the notch 55 with the idler recess 57. Upon the pintle 51 is arranged 5 a coiled spring 58, see Figures 5, 12 and 13. One end of this coiled spring is secured in the arm 54. The opposite end of said spring is secured in a locking nut 59, which is secured by a pin 60 to the pintle 51 in any 10 desired position of adjustment by passing the pin through corresponding holes in the locking nut 59 and the pintle 51. By this arrangement the spring 58 tends to throw the arm 54 yieldingly to the left in Figure 1. 15 Upon the shaft 41, see Figures 7 and 8, is adjustably secured a split boss 61, the ears of which are clamped on the shaft by a cap screw 62 in the usual way. As an additional 20 means for maintaining this boss in position on the shaft, a spline 77 is employed engaging the supplemental grooves in the inner face of the boss and the shaft in the usual way, see Figure 7. By this construction the boss 61 can be slid back and forth 25 on the shaft 41 and spline 77 and its arm 63 thus clamped in any desired position corresponding to any selected width of fabric being woven and at a distance from the edge of the selvage of the fabric at which 30 it is desired to have the filling cut. This is an important advantage since it does not interfere with the use of the loom for the production of any desired width of fabric within the capacity of the loom, but further 35 admits of positioning the cutter carried by said arm at the desired distance from the edge of the selvage for each fabric. Extending outward and upward from the boss 61 is an arm 63, which terminates in an angular extension 64, the upper face of which 40 is formed to hold a stationary cutting blade 65. 67 represents a movable cutting jaw pivoted to the fixed cutting jaw by a screw 68, see Figures 7 and 8. A spring 69, arranged on the shank of the screw 68 between the head of the latter and the face 45 of the movable cutter jaw 67, serves to maintain the two cutting blades 65 and 70 in proper contact with each other. 70 represents a steel cutting blade secured in any 50 desired way to the movable cutting jaw 67, see Figure 11. 71 represents a finger depending from the movable jaw and integral therewith. In the front face of this finger 55 and in the boss on the arm 63 are formed sockets 72, 73. 74 represents a coiled spring having one end arranged in the socket 73 and the other arranged in the socket 72. This spring normally tends to keep the 60 finger 71 to the left, see Figure 7, and the movable jaw with its cutting blade 70 in a raised or inoperative position. Upon the shaft near the boss 61 is secured a boss 75 by means of a set screw 76 and a spline 77, 65 see Figure 5. 78 represents an arm or lock-

ing dog projecting from the boss 75 and adapted for engagement with the locking notches 55, 56 of the lever 54.

Assuming the parts to be in the position shown in Figure 1, when the shaft 12 is turned through a short arc upon the operation of the feeler, as heretofore described, by reason of the connection between the shaft 12 and the shaft 41, lever 63 with its cutter is swung to the position shown in Figure 3, at the same time the locking dog 78 is moved in a direction opposite to the movement of the hands of a watch from the notch 56 to the notch 55.

In the loom as organized the feeler is 80 upon the left side of the loom while the cutter, the cutter mechanism and magazine are situated upon the right hand side of the loom. As the shaft 12 is operated due to the timing of the feeler, the shuttle 100, 85 see upper half of Figure 15, would be upon the left. At this time, that is at the commencement of the operation of the shaft 12, the cutter parts would be in the position shown in Figures 1 and 2. The 90 shuttle would then move to the right to the position shown in Figure 14, with the filling thread 80 of the spent spool positively located between the selvage and the shuttle in a predetermined position due to the 95 action of the spool tension 9 and the grip of the warp or selvage. This operation of the shaft 12 takes place while the lay is taking its reverse motion to the rear. The 100 shaft 12 shown in Figures 1 and 2 is operated at this time in a direction opposite to that of the hands of a watch, and by means of the gear segment 24, bell crank arms 35 and 36 and the gear segment 39 turns the shaft 41 also in a direction 105 opposite to that of the hands of a watch, throwing the cutter from the position shown in Figure 1 to the position shown in Figure 3, see Figure 4 for the position of the gear segment 24 and other connecting parts 110 at this time. The operation of the shaft 41 further turns up the arm 78 sufficiently so that it can be engaged by the notch 55 of the lever 54, the face 55 is brought down into engagement with arm 78 by means of 115 the spring 58, the parts assuming the position shown in Figure 3 and with that part of the filling 80 extending from the shuttle to the selvage in a predetermined position or plane, due to the co-action of the spool tension and the selvage, between the open jaws of the cutter. As the lay returns to beat up the filling it strikes the finger 71, operating the movable cutter blade 70 and shearing the filling 80, see Figure 4. As 120 the lay takes its backward stroke, the shaft 12 is given its reverse motion or the motion in the direction of the hands of a watch, and the parts carried by the lever 125 130 135 140 145 150 Figure 5 to the position shown in Figures 1 and 6, with the buffer member 23 engaging the upper end of the arm 54.

As the lay makes its return stroke to beat up the first shot of the filling out of the replenished spool, that part of the filling extending from the selvage to the weight 110 and herein designated 81 has been likewise positively positioned due to the co-action of the end tension 110 and the selvage between the jaws of the cutter and the lay, engaging the finger 71, operates the movable cutter blade 70, severing the filling 81, see Figure 5, and just at the end of its stroke, the lay engages the bunter 20, raising the lever 54 and permitting the spring 46 on the shaft 41 to turn said shaft in the direction of the hands of a watch, thus bringing the arm 78 down into the notch 56, or the original position as shown in Figure 1, and likewise returning the cutter to the position shown in Figure 1. This double cutting action with the motions of the parts as described takes place at each change of filling. Further, as stated, the parts are so arranged that the filling is positively cut each time at a predetermined distance from the selvage and due to the filling being positively positioned at a predetermined place at each cutting operation, the location of the cutter, the arrangement and timing of the co-operative parts.

In Figures 14 and 15, is further indicated, diagrammatically, a receptacle or magazine 101 for a series of charged filling spools 8 arranged one over the other. By hand or by automatic means, the exhausted filling spool 8 is ejected from the shuttle 40 and a charged spool inserted in the shuttle when the parts are positioned as in Figure 14. The details of this magazine 101 and the mechanism for shifting the spools of filling are not shown because forming no part of the present invention and being the subject of another application, the position of the magazine and its charged spools 8 being indicated in order to explain the position of parts at the time of the operation of the cutter.

Referring to Figure 16, the weight 110 attached to the end of each filling acts with the spool tension to keep the free end of the filling from kinking and to keep it in a predetermined plane until the filling has been caught by the warp, said weight or end tension thereafter acting with the warp or selvage to hold the said free end of the filling in a predetermined plane in position to be engaged by the cutter at any desired point adjacent the selvage. The spool tension 9, indicated in Figures 15 and 16, and the weight 110 or end tension located under the guide 11 in Figures 14 and 15, and shown in side elevation in Figure 16,

are each fully shown and described in my application, Serial No. 179,677, patented July 18, 1922, No. 1,422,897 of which this application is a continuation in part. The action of the spool tension 9 against the end tension or weight 110, as already stated, keeps the free end of the filling under control and in a predetermined position until the filling is caught by the warp, while the spool tension 9, acting with the warp, places and holds the unwoven end of the filling in a predetermined plane or position, engageable by the filling cutter at any desired point adjacent the selvage. The adjustability of the cutter arm 65, see Figure 12, together with the predetermined or fixed planes in which the filling is placed and held prior to and at the cutting operation, permits the automatic cutting of the end of the filling at the edge of the selvage or at any desired point remote therefrom within the range of the adjustment of the arm 65.

I claim:

1. In a loom organized for weaving wire fabric, and provided with an automatic filling replenishing mechanism, including automatic tension means acting on the uncut end of the spent filling and separate independently acting automatic tension means acting on the uncut end of the new filling for positively and successively positioning the uncut ends of the spent and then the new wire filling, a wire filling cutter, feeler-timed means for positively moving said cutter to operative position, means for holding said cutter in operative position during two beats of the lay to cut the last end of the wire filling of an exhausted filling unit and the free end of the wire filling of a succeeding filling unit, means to give said cutter its cutting operations, and means for thereafter returning the cutter to its inoperative position.

2. In a loom organized for weaving wire fabric and provided with an automatic filling replenishing mechanism, including automatic tension means acting on the uncut end of the spent filling and separate independently acting automatic tension means acting on the uncut end of the new filling for positively and successively positioning the uncut ends of the spent and then the new wire filling, a wire filling cutter mechanism comprising a feeler-timed oscillating shaft, an arm, one end of which is adjustably mounted on said shaft, cutter blades mounted on the opposite side of said arm, one of which is movable and arranged to be engaged by the lay to cut said filling.

3. In a loom organized for weaving wire fabric and provided with an automatic filling replenishing mechanism, including automatic tension means acting on the uncut end of the spent filling and separate inde-

pendently acting automatic tension means acting on the uncut end of the new filling for positively and successively positioning the uncut ends of the spent and then the 5 new wire filling, a wire filling cutter mechanism comprising a feeler-timed oscillating shaft, an arm, one end of which is mounted on said shaft, cutter blades mounted on the opposite end of said arm, one of which is 10 movable and arranged to be engaged by the lay to cut said filling, means for turning said shaft in one direction to position said blades in the plane of the uncut wire filling, and means for returning said shaft and said 15 blades to their initial position after the cutting operation.

4. In a loom organized for weaving wire fabric and provided with an automatic filling replenishing mechanism, including 20 automatic tension means for positively and successively positioning the uncut ends of the wire filling, a wire filling cutter mechanism comprising a feeler-timed oscillating shaft, a bunter mounted thereon, a second 25 oscillating shaft, connections between said two shafts for operating the second shaft in one direction, yielding means for operating the second shaft in the opposite direction, an arm carried by the second shaft and provided 30 with a wire filling cutter, means for holding the second shaft in position due to the operation of the first shaft and said yielding means, and means for operating said bunter to unlock the said mentioned 35 holding means.

5. In a loom organized for weaving wire fabric and provided with an automatic filling replenishing mechanism, including automatic tension means for positively and 40 successively positioning the uncut ends of the wire filling, a wire filling cutter mechanism comprising a feeler-timed oscillating shaft, a second oscillating shaft, connections between said two shafts for operating 45 the second shaft in one direction, yielding means for operating the second shaft in the opposite direction, an arm carried by the second shaft provided with a wire filling cutter, a latch secured to said second shaft, a movable arm provided with notches arranged to be selectively brought into engagement with said latch to hold the second shaft in corresponding positions, and a bunter mounted on the feeler-timed oscillating shaft 50 between the lay and said latch in position to be moved by the lay for releasing the latch from a notch in said movable arm.

6. In a loom organized for weaving wire fabric and provided with an automatic filling replenishing mechanism, including automatic tension means for positively and successively positioning the uncut ends of the wire filling, a wire filling cutter mechanism comprising a feeler-timed oscillating shaft, 55 a bunter carried thereby, a second shaft,

connections between said shafts for operating the second shaft in one direction, means for operating said shaft in the opposite direction, a latch carried by the second shaft, means engaged by second latch to hold the latter and the second shaft in position due to the action of the first shaft, the parts being so arranged that upon their return or further motion of said first shaft, said bunter is so positioned between the lay and said holding means that the lay by engaging said bunter causes the latter to release the latch from the holding means and permit the second shaft to return to its initial position. 70 75

7. In a loom organized for weaving wire fabric and provided with an automatic filling replenishing mechanism, including automatic tension means for positively and successively positioning the uncut ends of the wire filling, a wire filling cutter mechanism comprising an oscillating shaft, a gear segment fast thereon, a second shaft, a gear segment loose thereon, a part fast on said second shaft and engaging the gear segment thereon, connections between said part and the first named gear segment to turn the said second shaft in one direction, and a spring to return said second shaft to its initial position. 80 85 90

8. In a loom organized for weaving wire fabric and provided with an automatic filling replenishing mechanism, including automatic tension means for positively and successively positioning the uncut ends of the wire filling, a wire filling cutter mechanism comprising a shaft, a filling cutter supporting arm secured thereto, a locking member secured to said shaft, a spring arranged to turn said shaft in one direction, a power shaft, connections between said shafts for turning said first shaft a predetermined distance against the resistance of said spring, a complementary locking member arranged to engage the first named member to lock the first shaft in a predetermined position due to the action of the second shaft, a bunter carried by the second shaft in position to be engaged by the lay and to engage the complementary locking member, the parts being so arranged that the return or further movement of the second shaft moves said bunter in position to be engaged by the lay and thereby move the complementary locking member to release the first shaft and permit its spring to return said shaft to its initial 105 110 115 120 position. 125

9. In a loom organized for weaving wire fabric and provided with an automatic filling replenishing mechanism, including automatic tension means for positively and successively positioning the uncut ends of the wire filling, a wire filling cutter mechanism comprising an oscillating shaft, an arm, one end of which is mounted on said shaft cutter blades mounted on the opposite end of 130

8
said arm, one of which is movable and arranged to be operated by the lay to cut a filling; means for turning said shaft in one direction to position said blades in the plane of the uncut filling, means for locking the arm in said position during the cutting operation, and means for returning said arm to its initial position after the cutting operation.

5 10. In a loom organized for weaving wire fabric and provided with an automatic filling replenishing mechanism, including automatic tension means for positively and successively positioning the uncut ends of the wire filling; a wire filling cutter mechanism 15 comprising a feeler-timed oscillating shaft,

a bunter carried thereby, a second oscillating shaft, a gear segment fast on the first shaft, a gear segment loose on the second shaft, a bell crank connection between said gear segments, a part fast on the second shaft arranged to be engaged by said loosely mounted gear segment to move the second shaft in one direction, and a spring connected to said second shaft to move the latter in the opposite direction to bring said shaft to 25 its initial position.

In testimony whereof I have affixed my signature.

WILLIAM S. SOUTHWICK.
